UNITED STATES PATENT OFFICE.

ARCHIE M. AUGUSTINE, OF NORMAL, ILLINOIS.

DESIGN FOR A PEN-RACK.

SPECIFICATION forming part of Design No. 26,103, dated September 29, 1896.

Application filed August 10, 1896. Serial No. 602,362. Term of patent 7 years.

To all whom it may concern:

Be it known that I, ARCHIE M. AUGUSTINE, a citizen of the United States, residing at Normal, in the county of McLean and State of Illinois, have invented and produced a new and original Design for Pen-Racks; and I do hereby declare the following to be a full, clear, and exact description of the same, reference being had to the accompanying drawing, forming a part thereof.

The present invention has for its object to provide a new and useful design for pen-racks; and it consists in the design substantially as shown in the drawing and hereinafter described.

In the accompanying drawing, which represents a perspective view of a pen-rack embodying my design, A designates the inclined front portion, which forms a smooth flat tab-
let, its lower portion being concave, as shown at B. The inclined front portion A joins the

side supports C, which supports are tapering or inclined from the upper edges thereof to conform to the inclination of the inclined portion A. These tapering supports C extend 25 out some distance beyond the rear of the inclined front portion A and have scalloped edges D, which are disposed on an incline, as shown, thus forming a continuous tapering support. 30

Having now fully described my invention, what I claim as new, and desire to secure by Letters Patent, is—

The design for a pen-rack substantially as herein shown and described. 35

In testimony whereof I affix my signature in presence of two witnesses.

ARCHIE M. AUGUSTINE.
